United States Patent

Des. 241,679
Patented Sept. 28, 1976

241,679

TELEVISION RECEIVER

Richard K. Althans, Long Grove, and Melvin H. Boldt,
Glenview, Ill., assignors to Zenith Radio Corporation,
Chicago, Ill.

Filed Apr. 18, 1975, Ser. No. 569,522

Term of patent 7 years

Int. Cl. D14—03

U.S. Cl. D56—4 D

Fig. 1.

Fig. 2.

Fig. 3.

Fig. 4.

FIG. 1 is a front, top and partial left side perspective view of a television receiver showing our new design;

FIG. 2 is a right side elevational view, the left side being a mirror image thereof;

FIG. 3 is a top plan view; and

FIG. 4 is a rear elevational view.

The left side is identical to the right elevational view of FIG. 2.

We claim:

The ornamental design for a television receiver, substantially as shown and described.
